ANTI-KNOCK GASOLINE MANUFACTURE

Lionel S. Galstaun, Oakland, and Louis D. Rampino and William A. Vandenburg, Concord, Calif., assignors to Tide Water Oil Company, a corporation of Delaware

Application March 21, 1956, Serial No. 572,893

7 Claims. (Cl. 208—96)

This invention relates to the catalytic reforming of naphtha fractions to produce gasoline constituents of high anti-knock quality. More particularly, it relates to a combination of catalytic reforming and separation processes whereby a greater yield of high quality product is obtained than can be achieved by catalytic reforming alone. Still more particularly, it relates to an improved method for obtaining aromatic and other anti-knock hydrocarbons from catalytic reformates for the manufacture of high-octane motor fuel.

Progress in the automotive industry has resulted in the development of gasoline engines of higher and higher compression pressures, requiring gasoline fuels with correspondingly higher anti-knock properties or "octane rating." To meet this demand, the petroleum industry has developed various processes for producing gasoline of increased octane rating. One of the more efficient of such processes is catalytic reforming, wherein low-octane naphtha is contacted under pressure in the vapor-phase with suitable catalyst at temperatures above 800° F., in the presence of substantial volumes of hydrogen. A common type of catalyst used for catalytic reforming is platinum supported on a carrier of alumina and/or silica. Several such platinum catalysts are marketed which will produce good yields of 85 to 90 "research" octane number (ASTM Method D 908-53) reformate under operating conditions sufficiently mild that the catalyst can be used for extended periods of time without "regeneration" to remove carbon formed by undesirable reactions.

More recent developments in the automotive industry have created a need for gasoline having a research octane number substantially above 90 (before the addition of tetraethyl lead or other anti-knock compound) and preferably above 96. To meet this requirement by catalytic reforming processes now in use, it has been necessary to increase the severity of operating conditions to an extent that a substantial amount of hydro-cracking occurs with concomitant decrease in naphtha yield, increased equipment and operating cost to regenerate the catalyst (by burning off the carbon formed), and increased cost for a suitable catalyst capable of tolerating frequent regeneration without a prohibitive amount of deterioration.

In the present invention, certain new separation processes are combined with catalytic reforming to produce a higher yield of usable components for a 96 to 98 (or higher) octane gasoline that can be produced by catalytic reforming alone under conditions severe enough to produce the same anti-knock quality.

Heretofore, a large yield of high-octane blending components has been obtained by solvent-extracting the reformate (i.e., the liquid components emerging from the catalytic reformer) with a suitable extracting agent

2

to obtain a solvent extract of high aromatic content and then recycling the raffinate to the reforming step. In this prior-art process, the high-octane extract is, without further treatment, blended into the motor gasoline. An object of the present invention is to improve this prior art process markedly, so as to overcome a number of disadvantages inherent therein.

We have discovered that greatly improved efficiency can be obtained by subjecting only a middle fraction of the reformate to the extraction step and by using the light and heavy fractions (with or without further fractionation) directly in the gasoline. As a result of our new process, there is substantial saving in the cost of extraction and the size of the extraction equipment, a reduction of gums and other catalyst-inactivating agents in the reforming stage, and an improved finished gasoline blend.

We have found that the distribution of hydrocarbons in catalytic reformate conforms to the following pattern:

(1) There is a light portion distilling up to about 160° F. which contains only a small amount of aromatic hydrocarbons. It is predominate in paraffins, including isoparaffins, having reasonably high octane rating and excellent lead-susceptibility. The paraffins in this portion, however, are only with great difficulty improved by further reforming.

(2) A middle, or "heart-cut," portion distilling between about 160° F. and about 330° F. contains large quantities of aromatic hydrocarbons in admixture with similar amounts of paraffins having very low octane rating.

(3) A third portion distilling above about 330° F., is very highly aromatic and has inherently a high octane number in the region of 96 and above without tetraethyl lead. The aromatics contained in this portion are less readily separated from paraffins by extraction with solvents.

(4) There is usually a portion boiling above about 400° F. which is almost entirely aromatic. However, this portion generally contains substantial amounts of dicyclic aromatics such as naphthalene, the two methyl naphthalenes and the several dimethyl naphthalenes. We have found that the presence of these dicyclic aromatics in gasoline, even in low percentages (such as 1% or even less), is deleterious and causes varnishes, gums and lacquers in engines using such fuel. The aromatics contained in this fraction are likewise relatively difficult to separate from paraffins by solvent extraction.

Broadly, our invention contemplates fractionally distilling a catalytic reformate to isolate into separate fractions at least the first three, and preferably the four, portions described above. Fractions 1 and 3 are blended directly into gasoline. Fraction 2 is solvent refined, or otherwise treated, to extract therefrom the aromatic hydrocarbons, which are blended into gasoline. The raffinate from the extraction is again catalytically reformed, advantageously in the same reformer, to produce additional reformate. By these processing steps, the aromatics and the high-octane paraffins in reformate can be recovered for use in gasoline and substantially all the lower octane paraffins can be reformed to extinction, with a minimum of size, investment cost and operating expense of the solvent extraction plant. The extraction operation is most efficient, and the aromatic content of stocks charged to catalytic reforming is reduced to a minimum thereby enhancing the reforming operations. When, as is preferred, fraction number 4 is separated

and rejected, the objectionable dicyclic aromatics in normal reformates are eliminated from the finished gasoline.

Summarizing, the invention comprises catalytically reforming a naphtha, fractionating the reformate, extracting aromatics from a heart-cut thereof, and recharging the raffinate from the extraction to the reformer. This raffinate is substantially less in quantity than that usually obtained by solvent refining the whole liquid reformate, it is clean and contains substantially all the reformable paraffinic compounds that can be separated by extraction. In a preferred form of the invention, the heavy fraction obtained by fractionating the reformate is itself re-refracted to produce an overhead product of high aromatic content having a very high octane rating, and to reject a small amount of bottoms that tends to be harmful to engines. The overhead product from the re-refraction of the heavy fraction (or the entire heavy fraction where the "bottoms" components are not objectionable) is blended with the highly aromatic extract from the heart-cut. To this blend may be added the light fraction of the reformate in any amount required to meet volatility and octane requirements. If desired, the light fraction may be re-refracted and selected components thereof may be used in the finished gasoline blend, as the desired volatility and other characteristics of the blend demand.

Separation of the aromatics from the heart-cut may be by any suitable process, such as for example, by use of silica gel; by extractive distillation in the presence of phenol, cresylic acids, sulfolanes or glycol-water mixtures; or by solvent extraction (e.g. with liquid sulfur dioxide or diethylene glycol). The low anti-knock naphtha fed to the process may be a virgin naphtha or it may be a fraction produced from other refining processes such as hydrodesulfurization.

The invention may be more readily understood by reference to the drawing which is a diagrammatic flow diagram of the process. Naphtha in line 1, together with raffinate in line 2 and recycle hydrogen in line 3, is charged to catalytic reforming zone 4, wherein the mixture of hydrocarbons and hydrogen is passed at elevated pressure in the vapor phase through a bed of reforming catalyst at temperatures in excess of 800° F., and under suitable conditions of time and hydrogen concentration, to convert a substantial amount of the paraffinic charge to aromatic hydrocarbons with concomitant isomerization of some paraffinic constituents and production of hydrogen and certain low-boiling hydrocarbons. As is well known to the art, increased time and temperature and reduced pressures in catalytic reforming tend to increase cracking reactions with resulting formation of larger quantities of normally gaseous hydrocarbons and carbon. Preferably, the conditions in zone 4 are maintained sufficiently moderate to permit treatment of at least 30 barrels of naphtha per pound of catalyst. While such conditions vary with the naphtha treated and with the particular catalyst used, those conversant with catalytic reforming can readily select suitable conditions.

The effluent from the catalytic reforming zone 4, comprising hydrogen, normally gaseous hydrocarbons and normally liquid aromatic and paraffinic hydrocarbons, is discharged through line 5 into a main fractionating zone 6 which includes suitable traps, stills, absorption equipment and the like to fractionate the effluent into (1) a hydrogen fraction containing upwards of about 70% hydrogen, shown as leaving zone 6 through line 7; (2) a gas fraction composed principally of the C₁ to C₃ hydrocarbons formed in zone 4, but which may also contain some hydrogen and any excess C₄ hydrocarbons not usable in the finished gasoline, shown as leaving through line 8; (3) a light hydrocarbon fraction leaving through line 9; (4) a heart cut or middle hydrocarbon fraction, leaving through line 10, and (5) a heavy hydrocarbon fraction leaving through line 11.

Part of the hydrogen fraction in line 7 is recycled to the reforming zone 4 through line 3 to maintain the required ratio of hydrogen to hydrocarbon therein, in accordance with known principles. If desired, such hydrogen fraction may be treated to remove hydrogen sulfide or other unwanted impurities prior to entry into zone 4. The remainder of the hydrogen fraction in line 7 is passed through line 12 for any desired disposal. Likewise, the gas fraction in line 8 is disposed of as desired.

The light hydrocarbon fraction in line 9, may comprise approximately 25% of the total which leaves through lines 9, 10 and 11 and will be, generally speaking, those hydrocarbons which boil in the range between butane and about 160° F. and which contain less than about 20% aromatics. This fraction is not a useful source of aromatics upon further reforming and, due to the nature of catalytic reforming, contains high percentages of isoparaffins of good anti-knock value. These may be passed directly to blending zone 13 to be included in the finished gasoline or, optionally, part or all may be sent through line 14 to be used for other purpose.

The heart-cut, leaving the main fractionation zone 6 through line 10, may constitute approximately 50% of the total hydrocarbons leaving through lines 9, 10 and 11, being more or less dependent upon the composition of the crude naphtha and the desired characteristics of the finished blend. Normally, it includes an aromatic content that varies from about 10% to 20% in its lower boiling constituents to about 70% to 80% in its higher boiling constituents. It is substantially free from dicyclic aromatic compounds and other gum-forming substances. Its constituents will lie, generally speaking, within a distillation range from about 160° F. to about 330° F.

The medium-boiling hydrocarbons in line 10 are charged to an extraction zone 15. In the extraction zone 15, the hydrocarbons are separated into an extract (composed predominately of aromatic hydrocarbons, shown as leaving through line 16) and raffinate (composed predominately of paraffinic hydrocarbons, shown as leaving through line 2). As indicated prior, any one of the various well-known methods for separating aromatic from paraffinic hydrocarbons may be used for the separation in extraction zone 15. Extraction with diethylene glycol has proved suitable, and will be used elsewhere herein for illustration, though liquid sulfur dioxide and other extracting agents may also be used.

The extract in line 16 is passed to the blending zone 13 where it may be blended with the light hydrocarbons from line 9. The raffinate is returned through line 2 to the reforming zone 4 for further treatment. It is thus seen that the raffinate is treated to extinction, with the products of the process being a predominately aromatic gasoline and gas.

The heavy hydrocarbons which leave the main fractionation zone 6 through line 11 may comprise approximately 25% of the total hydrocarbons leaving through lines 9, 10 and 11. This heavy fraction is highly aromatic normally having 70% to 90% aromatic content or even more and having a very high octane number. However, this heavy hydrocarbon fraction also may contain naphthalene, alpha methyl naphthalene, beta methyl naphthalene and other dicyclic aromatics, which are undesirable either as gasoline components or as feed to the reformer and are preferably eliminated from both the raffinate and the blended gasoline. Hence, the heavy fraction may be passed from line 11 to a second fractionating zone 17 to remove therefrom a bottoms fraction indicated as being withdrawn through line 18. Generally speaking, the bottoms are those hydrocarbons which boil above 400° F. and may have a volume of about 1% to 5% of the liquid components leaving reforming zone 4. For a particular naphtha charge the proportions may differ, and what is desired is to exclude substantially all the

dicyclic aromatics from both the gasoline and the raffinate and to recover them in the bottoms, while recovering substantially all the valuable mono-cyclic aromatics in the gasoline. The predominate, overhead portion of the heavy hydrocarbons emerges through line 19 as high-octane, high-aromatics-content components that are passed to the blending zone 13.

Thus, the high-octane gasoline leaving blending zone 13 through line 20 contains a mixture of the high-octane clean components of the heavy hydrocarbons, line 19, and the predominately aromatic extract from the heart-cut hydrocarbons, line 16. As desired, part or all of the light hydrocarbons, line 9, or ingredients from other sources may be added in zone 13 for augmenting the quantity, correcting the volatility, or further improving the octane number.

To further illustrate the invention, the following examples of operations under typical conditions are presented.

EXAMPLE 1

About 7,300 barrels per day of a mixture of approximately 60% straight run naphtha and 40% thermally cracked naphtha, after catalytic hydrodesulfurization, is charged to a catalytic reformer together with about 2,700 barrels per day of raffinate obtained from a later stage of the process.

The naphtha mixture before hydrodesulfurization may have an ASTM distillation range of 170°-410° F. After hydrodesulfurization, the distillation range may be 130°-424° F. This stock is prefractionated to give a reformer charge having a distillation range of 160° to 400° F. After reforming, the resulting depropanized reformate may have a distillation range of 90° F. to 425° F.

The catalytic reforming is conducted with a typical platinum reforming catalyst under mild conditions. The hydrogen needed to maintain the desired hydrogen-to-hydrocarbon ratio during the reforming is obtained by recycling part of the hydrogen produced during the reforming reactions. The effluent from the reformer is cooled and passed to a high pressure gas separator from which a hydrogen stream of about 88% purity is withdrawn. Part of this stream supplies the recycled hydrogen, and the remainder (representing the main part of the hydrogen produced by reforming) is diverted to other uses.

The liquid hydrocarbons from the high pressure separator are stabilized at lower pressure to produce a gas stream composed of propane and lighter hydrocarbons, a stream containing the C₄, C₅, and C₆ hydrocarbons, a dehexanized heart-cut stream containing about 45% aromatic hydrocarbons and a stream containing heavy hydrocarbons boiling above about 330° F. The heart-cut is extracted by counter-current extraction with liquid sulfur dioxide at -25° F. to give about 2700 barrels per day of recycle raffinate containing about 5% aromatics and an extract stream of about 2740 barrels per day of dehexanized, highly aromatic blending stock (containing about 75% aromatics) having a clear research octane number of 99.7 suitable for use as a major constituent of high anti-knock gasoline or for other blending purposes as desired. Table I shows additional data relating to this example.

Table I

¹ Including 3.0% distillation loss.

It will be noted that the first portion of the reformate up to approximately 25% has a low aromatic content, i.e., less than 20%; the last 25% has a high aromatic content, i.e., more than 70%. The middle 50% portion has an average of about 50% aromatics. It will also be noted that the ASTM gum of all the overhead cuts was nil.

The bottom cut was further fractionated into 1% (of original charge) cuts with results shown in Table III.

Table III.—ASTM gum and dicyclic aromatic content of heavy fractions of reformate

60	Cut	Vol. percent of Charge	Percent Aromatics	ASTM Gum			Oct. No. plus 3.0 cc. TEL/gal.	Percent Di-cyclic Aromatics

¹ Cuts 3A through 6A are expressed as equivalent to isooctane plus the indicated amounts of tetraethyl lead.

Table III shows that the very heavy fractions of reformate all have high ASTM gum; the bottom 1% cut, which contained 64% dicyclic aromatics, showed 15.1% naphthalene and 45.4% alpha methyl naphthalene.

The relative tendency of reformate distillates to form gum is shown in Table IV.

7
Table IV.—ASTM gum of reformat distillates of different percents overhead

Percent Bottoms removed	ASTM Dist. ° F.	ASTM Gum	Research Octane No.	
			Clear	+3.0 cc. TEL/gal.
7	121-364	NH	80.5	93.2
5	122-374	1	81.2	93.6
2	126-386	1	82.2	94.0
1	125-396	1.4	83.0	94.5
0	125-411	10	85.0	94.5

The data in Table IV show that a reformat distillate corresponding to approximately 99% overhead would generally have satisfactory quality.

Where the light fraction is sent to the blending zone 13 through line 9, the composition of the fuel of this example may be as shown in Table V.

Table V.—Composition of blend from light, medium and heavy fractions

	Percent of Total	Boiling Range, ° F.	Research Octane No.	
			Clear	+3.0 cc. TEL/gal.
Light Fraction	32.8	C ₄ to 160	73	90.5
Extract from Medium Fraction	43.1	160-330	99.7	102.5
Overhead from Heavy Fraction	24.1	330-410	99.7	102.3
Total Blend	100.0	C ₄ to 410	90.9	98.5

Where the light fraction is withdrawn through line 14, the blend shown in Table VI is characteristic.

Table VI.—Composition of blend from medium and heavy fractions

	Percent of Total	Boiling Range, ° F.	Research Octane No.	
			Clear	+3.0 cc. TEL/gal.
Extract from Medium Fraction	64.2	160-330	99.7	102.5
Overhead from Heavy Fraction	35.8	330-410	99.7	102.3
Total Blend	100	160-410	99.7	102.4

This is a very high octane fuel, and marks a significant advance over the prior art.

EXAMPLE 2

To illustrate the comparative yields and quality of product when solvent extracting a 160° to 330° F. heart-cut of reformat in accordance with the invention and when solvent extracting a whole reformat according to conventional practice, the following data are presented from pilot plant tests. A reformat similar to that described in Example 1 was depentanized and extracted with diethylene glycol in a twenty stage counter-current Scheibel type pilot extractor. A 160° to 330° F. heart-cut (57.8%) of the same reformat was extracted in a separate test under comparable conditions. Data for the two operations are given in Table VII.

It will be noted that solvent treatment of the depentanized reformat yielded 46% of 99 octane gasoline, whereas the combination of heart-cut extract and heavy reformat provided 58% of equal quality gasoline blending stock.

This was accomplished while solvent treating only a heart-cut amounting to 57.8% of the depentanized reformat; and furthermore, the solvent to feed ratio required for treating the heart-cut was only 3.5 as compared to 5.5 for the whole depentanized reformat.

The savings in operating costs and in capital investment in solvent treating facilities are readily apparent. The cost of installing and operating the fractionating tower are minor in comparison to the comparable costs for solvent treatment.

The following engine tests illustrate the effect of removal of heavy ends of reformat on engine cleanliness. The test procedure involved a 40-hour engine run on a dynamometer under conditions chosen to correlate, on an accelerated scale, with field performance. In this test a 216.5 cubic-inch, six-cylinder Chevrolet engine was run continuously for forty hours at a speed of 1900 r.p.m. (plus or minus 25 r.p.m.) under an engine load of 36 B.H.P. (plus or minus 1 B.H.P.). The jacket coolant inlet temperature was kept at 155° F. minimum, the jacket coolant outlet temperature was kept within two degrees of 170° F., and the crankcase oil temperature was kept within two degrees of 190° F. The air-fuel ratio was 14.5 (plus or minus 0.5) to 1. The spark advance was 35° (plus or minus 3°). The spark plug gap, ignition cam angle, valve clearance, exhaust back pressure and other similar conditions were also maintained at predetermined values. Before the first test and between tests the engine was disassembled and cleaned, and a new set of piston rings was installed. The engine was given a standard two-hour break-in before the actual test was begun.

After each test run of forty hours, the engine was dismantled and inspected, and was rated on ten items, as follows:

- (1) Piston skirt varnish rating.
- (2) Cylinder wall varnish rating.
- (3) Intake valve stem deposit rating.
- (4) Intake valve tulip deposit rating.
- (5) Intake port deposit rating.
- (6) Overall engine sludge rating.
- (7) Overall engine varnish rating.

On these first seven items, the rating runs between 0 for dirty to 10 for clean.

(8) Corrosion or rust rating (10 for none, 9 for light, 8 for medium, and 7 for heavy corrosion).

(9) Stuck ring rating (10, minus 0.5 demerit for each 90° of ring stuck in the groove).

(10) Tight ring rating (10, minus 0.5 demerit for each tight ring).

A perfectly clean engine will thus rate 100. A total rating of 85 is considered acceptable if the piston skirt varnish is 7.5 or better. The test results are shown below:

Effect of fractionating reformat on engine cleanliness

	Overall Rating	Piston Skirt Varnish Rating	Demerits Due to Induction System Deposits	Induction System
70	90.5	8.5	2.0	Black Deposits, Clean.
75	95.5	9.0	1.0	Black Deposits, Clean.

To those skilled in the art, various changes and modifications of the invention may suggest themselves without departing from the spirit and scope of the invention. As stated prior, various alternates for solvent extraction are known, such as extractive distillation and selective adsorption. Part, or all, of the raffinate may be diverted from line 2 and used for other purposes, if desired, while retaining many of the advantages of the invention. Likewise, though the optimum cut-points for recovery of the intermediate fraction may be 160° F. and 330° F., as stated hereinbefore, substantial advantages from the invention would still be obtained even by a considerable variation from these figures.

We claim:

1. A process for producing highly aromatic anti-knock gasoline components which comprises: catalytically reforming, in the presence of hydrogen and at elevated temperatures, a naphtha fraction within the gasoline boiling range to convert a substantial portion of said fraction to aromatic hydrocarbons with the production of additional hydrogen, normally gaseous hydrocarbons and a liquid reformate having a boiling range extending from the normally gaseous hydrocarbons to above 400° F.; separating the resulting reformate into (1) a fraction having a boiling range below about 160° F. and containing less than about 20% aromatics; (2) a heart-cut middle fraction with a boiling range of about 160° to 330° F.; and (3) a heavy fraction having a boiling range above about 330° F. and containing more than about 70% aromatics; separating said middle fraction into a predominately aromatic portion and a predominately paraffinic portion; returning said predominately paraffinic portion to the reforming step; additionally fractionating said heavy fraction to recover an overhead substantially free of dicyclic aromatics and about 1% to 5% of bottoms boiling over 400° F. and containing substantially all the dicyclic aromatics of said reformate; and blending said predominately aromatic portion of said middle fraction and the overhead portion of said heavy fraction into gasoline.

2. A process for producing highly aromatic anti-knock gasoline components, which comprises: catalytically reforming, in the presence of hydrogen and at elevated temperatures, a naphtha fraction within the gasoline boiling range and having some components with boiling points above 330° F., to convert a substantial proportion of said fraction to aromatic hydrocarbons with the production of additional hydrogen, the reformed product having a distillation range extending above 330° F.; separating the resultant reformate into a low-boiling fraction consisting essentially of components boiling below 160° F., a relatively high-boiling fraction consisting essentially of components boiling above 330° F., and an intermediate fraction with a boiling range of about 160° F. to 330° F.; further separating said intermediate fraction into a predominately aromatic portion and a predominately paraffinic portion; returning said predominately paraffinic portion to the reforming step; and blending said predominately aromatic portion into gasoline.

3. The process of claim 2 in which at least a major portion of the high-boiling fraction is also blended into the gasoline.

4. A process for producing highly aromatic anti-knock gasoline components which comprises: catalytically reforming, in the presence of hydrogen and at elevated temperatures, a naphtha fraction having some components boiling above 330° F., to convert a substantial portion of said fraction to aromatic hydrocarbons with the production of additional hydrogen, the resulting reformate also having some components boiling above 330° F.

and containing a detrimental amount of dicyclic aromatics boiling above 400° F.; separating the resultant reformate into a relatively low-boiling fraction boiling below 160° F., a relatively high-boiling fraction boiling above 330° F., and an intermediate fraction boiling from about 160° F. to about 330° F.; separating said intermediate fraction into a predominately aromatic portion and a predominately paraffinic portion; returning said predominately paraffinic portion to the reforming step; distilling said high-boiling fraction to remove as overhead constituents having a distillation range of about 330° F. to 400° F., and to leave a bottoms portion of about 1 to 5% by volume of the reformate and having a boiling point over 400° F., and blending said predominately aromatic portion of said intermediate fraction and said overhead.

5. A process for producing highly aromatic anti-knock gasoline components which comprises: catalytically reforming, in the presence of hydrogen and at elevated temperatures, a naphtha fraction including some components boiling above about 330° F., to convert a substantial portion of said fraction to aromatic hydrocarbons with the production of additional hydrogen and some deleterious dicyclic aromatics; separating the resultant reformate into (1) a low-boiling fraction whose components boil below 160° F. and which contain relatively small proportions of aromatics and a major proportion of hydrocarbons substantially incapable of producing aromatics by further reforming; (2) a heart-cut middle fraction with a boiling range of about 160-330° F.; and (3) a heavy fraction whose components boil above 330° F.; separating said middle fraction into a predominately aromatic portion and a predominately paraffinic portion; returning said predominately paraffinic portion to the reforming step; distilling said heavy fraction to remove a small bottoms portion between 1% and 5% of the volume of the liquid reformate and boiling above 400° F. and containing substantially all the dicyclic aromatics of said reformate; and blending together at least said predominately aromatic portion of said middle fraction and the overhead obtained from distilling said heavy fraction.

6. In a catalytic reforming process for producing anti-knock gasoline components wherein a catalytic reformate having a boiling range from about 100° F. to above 400° F. is solvent extracted into an aromatic extract and a paraffinic raffinate and the resulting raffinate is recycled to the reforming process, the improvement comprising subjecting to the extracting step only a 160°-330° F. heart-cut of said reformate, to obtain a raffinate for the recycle step substantially free of dicyclic aromatics and of paraffinic hydrocarbons boiling below about 160° F.

7. In a catalytic reforming process for producing anti-knock gasoline components wherein a catalytic reformate having components boiling above 330° F. is fractionated to provide a portion boiling below about 330° F. and a portion boiling above 330° F., the improvement comprising further distilling the higher boiling portion to distill therefrom an overhead product leaving a bottoms product boiling above 400° F. and containing not over 5% by volume of said reformate and including substantially all the dicyclic aromatics of said reformate, and blending said overhead in gasoline.
